UNITED STATES PATENT OFFICE.

JOHN C. BROWNE, OF LONDON, ENGLAND.

SAFETY-SHIP.

SPECIFICATION forming part of Letters Patent No. 236,302, dated January 4, 1881.

Application filed November 10, 1880. (No model.) Patented in England June 14, 1879.

To all whom it may concern:

Be it known that I, JOHN COLLIS BROWNE, a subject of the Queen of Great Britain, residing in London, England, have invented 5 new and useful Improvements in the Construction of Safety-Ships, (for which I have obtained a patent in Great Britain, No. 2,358, bearing date June 14, 1879,) of which the following is a specification.

10 The object of my invention is to construct vessels with overhanging bilges as air-tight compartments, and attaching them to vertical girders running from end to end on each side. Longitudinal concave channels are formed 15 under these bilges, within which screw-propellers can work, these being on shafts set at an angle through the sides of the hull, and worked direct by engines.

The curved frames of my vessel terminate 20 at the vertical girders, and longitudinal outside stringers are connected to the frames of the hull and to the frames of the overhanging bilges to give strength along where the butt-seams of the two frames are situated. 25 The transverse beams are attached to the frames of the hull, other or inside stringers, of angle-iron, securing the beams to the vertical girders.

The bottom of my vessel is flattish, and may 30 have an extended or plow prow in advance of the bow proper, said prow having a flattish base and sloped upper surfaces on each side of its central line to divide the water and to guide it under the overhanging bilges for producing steadiness while the vessel is under steam. I fit uprights on the beams and form 35 side passages between them and the vertical girders, decks being arranged over the passages.

40 In the annexed drawings, Figure 1 represents a section of my vessel.

A A are the overhanging bilge-frames, to which are riveted the partitions B B, to form compartments along the sides.

45 C C are the vertical girders, to which the frames A A are riveted, the girders being also attached to the beams D D by angle-iron stringers E E.

50 F F are outside stringers, overlapping the seams and connecting the butt-ends of the bilge-frames A A and of the frames G G of the hull.

H H are uprights upon the beams D D, spaces I I being formed between the said uprights H H and the vertical girders C C to 55 serve as passages, or as berths, if partitioned off.

J J are decks over the passages I I, and K is a higher deck, giving room under it and along the center of the vessel for saloon or 60 other purposes.

L is the bottom, of flat form, shaped from the frames of the hull.

M M are screw-propellers, arranged in the concave channels or shafts N N, set at an 65 angle through the sides of the hull at about midship, so that the screws are always submerged and protected from injury.

Fig. 2 shows a modification in which the hull-frames G G are sufficiently long to form 70 the frames of the overhanging bilges; also, whereby the outside stringers F F are dispensed with, the beams D being provided with flanged knee-pieces for the attachment of the hull-frames G G and the vertical girders 75 thereto.

I am aware that it is not broadly new to arrange rotating propeller-shafts at an angle within channels on opposite sides of the hull of a vessel, as in English Patent No. 3,997 of 80 1875, and such, therefore, I disclaim.

I claim as my invention—

In the construction of ships, the combination of the vertical girders C C, extending from end to end of the vessel, the overhanging bilge-frames A A, connected with the girders, the partitions B B, attached to the bilge-frames and forming air-tight compartments throughout the length of the overhanging bilge-frames, and the hull-frames G G, connected with the lower portions of the latter and extending in a curved plane to the flat bottom H, for forming longitudinal continuous concave side channels below the overhanging bilge-frames, within which are arranged the propeller-shafts, all substantially as and for the purpose described. 95

In witness whereof I have hereunto signed my name in the presence of two subscribing witnesses.

JOHN COLLIS BROWNE.

Witnesses:

HENRY GARDNER,
HENRY J. GARDNER.
